UNITED STATES PATENT OFFICE

ARTHUR N. PLANTE, OF HARTFORD, CONNECTICUT

COMBINATION TOOL

Application filed February 24, 1927. Serial No. 170,567.

This invention relates to combination tools and has for its object the provision in a tool, primarily useful as a wrench, of lever operated linkage associated with the jaws of such a tool whereby the user may impart to the jaws through slight manual pressure a powerful gripping action suitable to make the tool also useful as pliers or a wire cutter as will hereinafter more fully appear. The invention which is similar to the devices disclosed in my prior Patent No. 1,725,301, of August 20, 1929 and a subsequent application Serial No. 301,650 filed Aug. 23, 1928, comprises various novel features of construction clearly set forth in the following detailed description and illustrated in the accompanying drawings, in which,—

Figure 1, is a side view of a tool embodying the preferred form of my invention. Figure 2, is a front edge view of the tool shown in Fig. 1. Figure 3, is a view similar to Fig. 1, with certain parts shown as broken away or in section. Figure 4, is a side view of a modified form of my invention. Figure 5, is an end view of the tool shown in Fig. 4. Figure 6, is a detail view in isometric projection with various parts separated and arranged to clearly show their order of assemblage,—and Figures 7 and 8, are side views of other modified forms of my invention.

Referring to the drawings the preferred form of my invention will first be described. Wrench jaws similar to those in a common form of tool are designated by 1 and 2. The head or jaw 1, is provided with a shank 3, divided longitudinally or bifurcated to form the guides or furcations 4 and 5. The head and shank may be formed from a single piece of metal or built up of sections and held together as with rivets 6.

Means for actuating the jaw 2, include a lever and link hereinafter fully described which act against a normally stationary fulcrum member 7. In order to maintain an aligned and compact assemblage of the shank, movable jaw and fulcrum member, the latter two are channeled on opposite sides to receive respectively the furcations 4 and 5, and to form respectively in each a web portion as 8 and 9. These web portions are each sub-

stantially equal in thickness to the space between the furcations and in the adjacent ends of said members the web is recessed as at 10 and 11, to receive the ends respectively of links 12 and 13, which links are similarly joined together as at 14, and of a thickness equal to the web portions so that the linkage formed by the several members may be aligned by the furcations and maintained thereby in operable assemblage. A handle 15, together with link 12, constitutes a lever for operating the linkage of which it forms a part. Said handle may, as shown, be secured as by rivets 16, to an extension 17 of the link 12, to receive which the handle is slotted at 18. The walls of this slot 18, laterally support the adjacent part of link 13, and edgewise this link is further supported by the contiguous edge of the extension 17.

As already intimated the link forming end 12, of the operating lever, is laterally contiguous to opposed walls of the furcations which latter form desirable support for the lever as a whole. Any suitable means may be provided for adjusting the fulcrum member 7 on the shank 3, and as shown, it comprises a screw 19, carried by the fulcrum member and meshing with threads 20, on the shank. The screw is pivoted in a recess of the fulcrum member on a pin 21. As a cover 22, for the fulcrum member a suitably folded piece of sheet metal may be secured thereto by the rivets 23. One of these rivets may serve also to prevent displacement of the pivot pin 21. From the foregoing description it will be clear that the jaw 2 may be moved toward its complementary jaw by pressing handle or lever 15 from the position in which it is shown in Fig. 1 to the position in which it is shown in Fig. 3. The movement thus

imparted is comparatively slight but entirely sufficient inasmuch as any required closure of the jaws may be approximated through screw adjustment of the fulcrum member along the shank 3. For a given location of the fulcrum member on the shank, the minimum distance between complementary jaws 2 and 3 is effected when the pivotal joints of the linkage involved are in dead center alignment and as will be seen from Fig. 3, this re-

lation of the parts exists just before the handle 15, as at 15' (see Fig. 3) engages the shank as a stop against further closing movement, so that when contact of the handle and shank is finally established the center joint 14, of the links is sufficiently beyond the dead center line as to lock the jaws upon a nut or other object with a vise-like grip. With the fulcrum member adjusted so that the jaws will just come together when fully extended by the lever mechanism the action of the tool is appropriate for cutting wire and it may be suited to this purpose by forming on the jaws cooperative cutting edges 24 and 25.

15 In the modified form of my invention shown in Figs. 4 and 5, the action is identical with that of the tool already described. It differs slightly in construction in that the links between the jaw 26 and fulcrum member 27, are of different form and are connected to said members and to each other by pivot forming rivets. The jaw link member 28, is U-shaped in transverse section and is extended to form a handle 29, which is 25 adapted to shut over and enclose a part of fulcrum member 27. The U-shaped section at the forward end of this handle or lever, straddles the movable jaw and is pivoted thereto by rivet 30. Connection between lever 29 and fulcrum member 27, comprises oppositely disposed links 32 and 33, which are respectively pivoted to side flanges of the lever by rivets 34 and 35, and to the fulcrum member by a rivet 36. The latter extends 30 through the fulcrum member and by securing the opposed links also serves to secure the casing 37 to said member.

In the modified form of tool shown in Fig. 7, the link and lever member 40, is provided 40 with the cam surface 41, which acts against the roll 42, associated with fulcrum member 43. As the lever is moved toward its closed position the cam forces jaw 44, toward the complementary jaw 45. Similarly in the modified form of the invention shown in Fig. 45 8, the handle or lever 50, pivoted to jaw 51, is provided with a cam surface 52, operable against pin 53, carried by fulcrum member 54, to move said jaw toward the complementary jaw 55.

50 While I have shown several forms of embodiment of my invention it is distinctly to be understood that many other changes may be made in the form and arrangement of the various elements without departure from the scope of the invention as defined by the appended claims.

Having thus described my invention, what I claim is,—

60 1. A tool including in combination a head or jaw having a bifurcated shank, a jaw channeled on opposite sides to receive respective furcations of the shank, a fulcrum member similarly channeled to receive the shank, toggle linkage interposed between the shank, and

fulcrum and jaw members, means for securing the fulcrum against movement relative to the shank, and means for moving the toggle linkage into substantially dead center alignment longitudinally of the shank. 70

2. A tool including in combination a head or jaw having a bifurcated shank, a jaw channeled on opposite sides to receive respective furcations of the shank, a fulcrum member similarly channeled to receive the shank, toggle linkage connecting the fulcrum and channeled jaw member held in operative relation by and between the furcations, means for securing the fulcrum against movement relative to the shank, and means for operating the toggle linkage. 75

3. A tool including in combination a head or jaw having a bifurcated shank, a jaw channeled on opposite sides to receive respective furcations of the shank, a fulcrum member similarly channeled to receive the shank, toggle linkage connecting the fulcrum and channeled jaw member, and a casing secured to the fulcrum member and extending over the furcations. 80

4. A tool including in combination a head or jaw having a bifurcated shank, a jaw channeled on opposite sides to receive respective furcations of the shank, a fulcrum member similarly channeled to receive the shank, a link pivotally connected to one of said channeled members, a lever pivotally connected to the other channeled member, said link and lever being also pivotally connected to each other, each pivotal connection comprising a pintle on one member matching an opening in the other whereby the linkage formed when the parts are engaged may be disposed between the furcations and maintained in operable assemblage thereby, and means for adjusting the fulcrum on the shank. 90

5. A tool including in combination a head or jaw having a bifurcated shank, a jaw channeled to receive respective furcations of the shank, a fulcrum member similarly channeled to receive the shank, and jaw actuating means interposed between the jaw and fulcrum members, said means including a lever which at one end is laterally contiguous to and supported by walls of the furcations. 105

6. A tool including in combination a head or jaw having a bifurcated shank, a jaw channeled to receive respective furcations of the shank, a fulcrum member similarly channeled to receive the shank, toggle linkage interposed between the jaw and fulcrum members, and a handle associated with the toggle linkage and movable toward the shank to close the jaws, said handle and shank forming stop means operable to lock the toggle linkage in substantially dead center alignment. 110

120 In testimony whereof I affix my signature.
ARTHUR N. PLANTE. 125
